UNITED STATES PATENT OFFICE

2,438,859

MOISTURE RETAINING PAD FOR AIR
COOLING DEVICES

Martin E. Marsalis, Fort Worth, Tex.

Application September 14, 1945, Serial No. 616,184

3 Claims. (Cl. 299—20)

1

This invention relates to air cooling equipment and it has particular reference to moisture retaining pads employed in air cooling and conditioning devices through which the air is drawn by means of a suitable fan, or the like, and its primary object resides in the provision of a pad construction in which is incorporated a water conduit having both inlet and discharge openings whereby the pad is kept moist and providing a rigid frame for the said pad.

An object of the invention is that of providing a unique cooling pad construction which is both compact and rigid and capable of being employed in any type of air cooling equipment utilizing water as a cooling agent for the air drawn through the pad by any conventional means.

Another object of the invention resides in the provision of a corrugated baffle arranged along the upper end of the tubular frame and above the water discharge orifices whereby the liquid is broken up into droplets and directed downwardly upon the moisture retaining material of the pad to evenly and thoroughly saturate the same and maintain such saturation at all times.

Broadly, the invention seeks to comprehend the provision of a moisture retaining air cooling pad which is embodied in a compact unit including a tubular frame through which the moistening liquid is conducted, as well as affording a rigid mounting for the pad, and providing a readily detachable unit which can easily be adapted for any type of air conditioning equipment of the character described.

While the foregoing objects are paramount, other and lesser objects will become manifest as the description proceeds, taken in connection with the appended drawings wherein:

Figure 1 is a front elevational view of the invention illustrating, in cutaway sections, the manner of construction and showing the corrugated baffle, partially cut away, at the top of the frame.

Figure 2 illustrates a side or edge view of the invention showing the tubular frame and foraminous envelope embracing the entire unit.

Figure 3 is a lateral cross-sectional illustration, taken on lines 3—3 of Figure 1, showing both fabric and wire mesh envelopes on the pad and illustrating the manner in which the same are retained thereon, and

Figure 4 fragmentarily shows, in perspective detail, the form of the baffle and its relationship to the discharge orifices in the upper end of the frame.

2

The invention contemplates the provision of a tubular frame 10, preferably rectangular in form but having rounded corners 11. The frame 10 may be formed of such material as copper tubing of any desired gauge and rigidity and has a liquid inlet 12 to which may be attached a hose (not shown) or any suitable connection by which water can be introduced into the tubing. It is desirable to connect the inlet 12 to a water supply pipe and provide a suitable valve therefor whereby the supply and flow of the liquid can be properly regulated. It is preferable to place the inlet 12 near the bottom of the frame 10, as shown in Figures 1 and 2. The end of the tubing opposite the inlet 12 is closed.

Along the top of the frame 10 is arranged a series of relatively small orifices 13 providing outlets for the liquid introduced through the inlet 12. A baffle 14 is arranged along and above the upper end of the frame 10 and is substantially inverted U-shaped, as shown in Figure 2, and provides a box-like hood above the orifices 13. It is desirable to corrugate the baffle 14 to provide miniature vertical troughs 15 along each side, as shown in Figure 4, the purpose and function of which will presently become manifest.

A pad 16, comprising a fibrous moisture retaining material 17, such as excelsior, or the like, is arranged within the frame 10 and is designed to extend to all its sides and completely fill the same as shown in Figure 1. A covering of fabric 18 is first placed about the material and the entire assembly, including the frame 10, is enveloped in a wire mesh 19, in the manner illustrated in Figure 1. The foraminous envelope 19, the fabric 18 and the fibrous filler 17 are tied through at intervals with strong cord or wire 20, in the manner shown in Figures 1 and 3.

The result of the arrangement just described is a unified assembly which is rigid and durable yet sufficiently porous to permit the passage of air therethrough in sufficient volume to provide adequate cooling when the filler 17 is impregnated with moisture. A plurality of mounting brackets 21 are spaced about the frame 10 by which the same can be mounted in a cabinet (not shown) in which a fan may be arranged.

In operation, when water is introduced in proper volume through the inlet 12 into the frame 10, the liquid will flow through the orifices in tiny streams and impinge upon the inner walls of the baffle 14 thereabove and be broken up or atomized into small droplets which run down the miniature troughs 15 and drop on the

pad 16. The corrugated sides of the baffle 14 also function to prevent the liquid from running along their lower edges *a* and dropping off at either end in event the assembly is not level as would be the case if the edges *a* were smooth.

The troughs 15 insure an even distribution of moisture all along both sides of the pad 16 which will penetrate the full length and breadth thereof and thus afford a uniform moisture impregnated screen drawn therethrough can be washed and cooled and dust particles excluded.

It is contemplated that the cabinet in which the invention is to be installed is provided with a collector trough or other suitable means of receiving the water which may drip from the bottom of the pad 16. Such an arrangement, obviously, is conventional.

Manifestly, the construction herein shown and described is capable of considerable changes and modifications by persons skilled in the art without departing from the spirit of the invention or the scope of the appended claims.

What is claimed is:

1. In a moisture pad for cooling devices, the combination with a tubular frame having orifices in portions thereof mounting brackets therefor, a porous moisture retaining material arranged in the said frame and having substantially the same thickness as the said frame to form a pad, a fabric covering enveloping the said pad and a wire mesh covering the said fabric and the said frame, means tying the said pad and coverings in a compact unit and means for admitting a liquid into the said tubular frame to be discharged through said orifices.

2. In an evaporator for air cooling apparatus,

the combination with a tubular frame capable of having a fluid conducted therethrough and having discharge orifices in portions thereof and mounting brackets for said frame, a moisture retaining pad arranged in said frame and having substantially the same thickness as said frame, a fabric covering for said pad and a wire mesh covering said fabric and said frame, means tying said pad and coverings in a compact unit, and means for admitting a fluid into said tubular frame to be discharged through said orifices.

3. In an evaporator device for air cooling apparatus, in combination with an air cooling pad of an absorbent material and a tubular frame therefor capable of conducting a fluid therethrough, discharge orifices for said fluid arranged along the upper horizontal member of said frame over said pad, a fluid baffle arranged longitudinally of said horizontal member above said orifices and having corrugated flanges depending on each side of said member, the corrugations in said flanges defining troughs directing fluid droplets onto said pad therebeneath.

MARTIN E. MARSALIS.
